Attorneys,

UNITED STATES PATENT OFFICE.

MICHAEL LOFTUS, OF CHICAGO, ILLINOIS.

NON-REFILLABLE BOTTLE.

No. 838,035.

Specification of Letters Patent.

Patented Dec. 11, 1906.

Application filed March 1, 1906. Serial No. 303,649.

To all whom it may concern:

Be it known that I, MICHAEL LOFTUS, a citizen of the United States, residing at Chicago, in the county of Cook and State of Illinois, have invented new and useful Improvements in Non-Refillable Bottles, of which the following is a specification.

This invention is a valve construction for non-refillable bottles, the principal features being a hollow air-tight member consisting of a bulb with a stem and a flange supported by a valve-disk, and above the bulb is a glass weight which normally keeps the valve closed.

15 In the accompanying drawings, Figure 1 is a vertical section of a bottle having my device. Fig. 2 is a sectional detail of the valve. Fig. 3 is an enlarged cross-section on the line 3 3 of Fig. 1.

20 Referring to the drawings, 10 indicates the body of the bottle, and 11 is the neck thereof, which is provided with an internal annular flange 11^a, which forms the valve-seat.

12 is a permanent stopper which is inserted 25 and cemented in a screw-threaded part 11^b at the top of the bottle and is provided with an opening 12^a for a cork.

13 is a valve-disk, which is preferably made of rubber or any other similar material 30 and which seats upon the flange 11^a.

14 is a hollow member consisting of a hollow glass bulb 14^a, having a hollow stem 14^b extending through the valve-disk 13 and at its bottom flared or flanged, as at 14^c, the bulb and stem being air-tight and all, including the flange, being integral.

15 is a weight or plunger for normally keeping the valve closed and to prevent refilling of the bottle through its top. This 40 weight 15 is of glass and is square or rectangular in cross-section; but any multisided shape may be used. The top of the weight is provided with cross-grooves 15^a, which

provide outlets and prevent the weight from closing the opening 12^a at the top when the 45 bottle is inverted or turned over for pouring out the liquid.

When the bottle is turned over to pour out the liquid, the fluid strikes the flange 14^c on the hollow member 14, which raises or causes 50 the valve to leave its seat, the plunger 15 at the same time sliding to the open end of the bottle. The fluid may then be poured out. Attempt to refill the bottle causes the valve to close against its seat by reason of the 55 weight 15. Attempt to force liquid in with the bottle inverted will cause the hollow member to float and close the valve.

Directly under the weight 15 the neck of the bottle has an inwardly and upwardly 60 projecting rib 16, which serves to prevent the insertion of a wire or the like under the valve to lift the same. Should such a wire be inserted down beside the weight, the end thereof will engage the rib, and thus prevent 65 the wire from reaching the valve.

I claim—

1. In a bottle, the combination of a valve-seat formed in the neck thereof, a disk valve which closes against said seat, a float comprising a hollow bulb having a stem extending through the disk, and a weight in the neck above said float.

2. In a bottle, the combination with a valve-seat formed in the neck thereof, of a valve which closes against the seat, a weight above the valve, and an inwardly-projecting annular rib extending around the neck under the weight.

In testimony whereof I have signed my 80 name to this specification in the presence of two subscribing witnesses.

MICHAEL LOFTUS.
